UNITED STATES PATENT OFFICE.

SIMEON K. DICKERSON, OF CLEVELAND, OHIO.

CAR-COUPING.

1,087,222.

Specification of Letters Patent. Patented Feb. 17, 1914.

Application filed December 11, 1912. Serial No. 736,071.

To all whom it may concern:

Be it known that I, SIMEON K. DICKERSON, a citizen of the United States, residing at Cleveland, in the county of Cuyahoga and State of Ohio, have invented certain new and useful Improvements in Car-Couplers, of which the following is a specification.

The invention relates to car couplers, and more particularly to that portion of the coupler known as the coupler pocket. It has for its primary objects, the provision of an improved form of pocket having a supporting shelf and capable of reversal; the provision of a pocket of the character specified which can be reversed to suit bumper beams located at different heights, or which may be reversed on the same bumper beam to give an adjustment in the height of the bearing face of the shelf. The pocket is particularly designed for use with locomotives and tenders, but it will be understood that the device is not limited to such use. One embodiment of the invention is illustrated in the accompanying drawings wherein—Figure 1 is a side elevation of the coupler pocket, with a coupler head connected thereto, Fig. 2 is a side elevation of the coupler pocket alone, and in reversed position upon a bumper beam having a different height above the track than the bumper beam of Fig. 1, Fig. 3 is a half plan view of the coupler pocket, and Fig. 4 is a plan view of the detachable supporting shelf employed in the pocket.

The coupler pocket comprises a base portion 1 adapted to bear against the usual bumper beam 2; a socket portion 3 adapted to receive the shank of the coupler head, and a supporting shelf portion 4. The coupler head 5 may be of any approved form, and is provided with a shank 4 fitting into the socket 3 and secured in position by means of the usual pin 6.

The supporting shelf 4 is provided upon its upper face with a bearing surface 7 (Fig. 4) adapted to lie beneath and engage the portion 8 of the coupler head, and is suitably stiffened by ribs and provided with bolt holes 9—9 and 10—10. Bolts 11—11 with counter sunk heads extend through the holes 10—10 and through the bottom wall of the socket 3, and such bolts 11—11 take the weight imposed upon the shelf by the coupler head. Other bolts 12—12 extend through the holes 9—9 and through corre-

sponding holes in ribs 13 carried by the 55 socket 3. The weight upon the shelf tends to force the left hand end of such shelf upward, and in order to oppose this movement spacing sleeves 14 are provided around the 60 bolts 12.

By reference to Fig. 1 it will be seen that the socket 3 which carries the shank of the coupler head is placed off center with respect to the base 1 of the pocket, the center line A of the socket 3 lying closer to the bottom edge of the base 1 than to its upper edge. The base plate is held in position by means of bolts 15 and 16, and the center line of the bolt 16 is nearer to the center line A of the pocket than is the center line of the 70 upper bolt 15. As a result of this unsymmetrical placing of the base 1 and its securing means with respect to the socket, it will be seen that when the base plate 1 and the socket 3 carried thereby are reversed, the 75 center line of the socket is shifted upward, thus giving a vertical adjustment of the socket. This reversal of the device brings the supporting shelf 4 uppermost, in which position it would interfere with the portion 17 of the coupler head, and would cease to be of service in supporting the coupler head. The construction as heretofore indicated, permits of its removal, and as the other side of the socket 3 is formed similarly to the side 80 which carries the shelf, the plate may be secured to such other side, the front bolts 11—11 at such time passing through the holes 18 through the upper wall of the socket 3. It will therefore be apparent that by the 85 foregoing procedure the pocket may be reversed in position upon its beam, and that in so reversing the pocket the center line of the socket is shifted vertically a given distance, depending upon the amount the base 1 is off 90 center with respect to the socket. The rear bolts 12 would be of course shifted to the other side of the ribs 13 when reversal occurs. This shift of adjustment might be desirable for various reasons, such as wear 100 upon the tires of the wheels, sagging of springs, or other causes tending to produce a downward movement of the body of the tender, locomotive, or car to which the bumper beam is attached.

The feature of reversal also permits the application of my coupler pocket to bumper beams of different heights, while still main-

taining the center lines of the socket portions of the devices upon the same level. This will be readily understood by comparison of Fig. 2 of the drawing with Fig. 1, Fig. 5 2 of the drawing, illustrating the coupler pocket applied to a bumper beam 2' lying at a level below that of the bumper beam 2 of Fig. 1, while yet maintaining the socket portions with the common center line A. 10 It will be seen that in Fig. 2 the device has been inverted, and that the pocket is thus elevated a sufficient distance to compensate for the lower level of the bumper beam 2'. The supporting shelf 4 fits equally well upon 15 either side of the pocket 3, and in both positions its bearing face which engages the portion 8 of the coupler head is at the same distance from the center line A of the socket. The structure as heretofore described is of 20 course merely illustrative of the broad principle of invention involved, and the specific structure may be widely modified without departing from the invention, which comprehends broadly the use of a socket portion 25 with its base or the securing means therefor off center with respect to the center line of the socket, in connection with a removable supporting shelf adapted to be secured either to the upper or to the lower 30 side of the socket, so that the device will be provided with a supporting means for the coupler head when the pocket is reversed.

Having thus described my invention and illustrated its use, what I claim as new and

desire to secure by Letters Patent, is the following:

1. In combination in a coupler pocket, a socket portion having similar bearing faces upon its upper and lower sides at the same distance from the center line of the socket, a supporting shelf having a bearing face upon one side adapted to fit either one of said similar bearing faces, means for securing the shelf detachably in position with its bearing face engaging either one of said bearing faces on the socket, and a base portion located off center vertically with respect to the center line of the socket. 40

2. In combination in a coupler pocket, a socket portion having bearing faces upon its upper and lower faces, a supporting shelf for the coupler head adapted to engage either of said bearing faces, means whereby the shelf may be secured to either one of the bearing faces, and a base portion having bolt holes above and below the center line of the socket, the holes above the center line being at a distance therefrom different from the distance of the holes below the center line 45 from such center line.

In testimony whereof I have hereunto signed my name in the presence of the two subscribed witnesses.

S. K. DICKERSON.
